UNITED STATES PATENT OFFICE.

HUGO PICK, OF CHICAGO, ILLINOIS, ASSIGNOR TO ALBERT PICK & COMPANY, OF CHICAGO, ILLINOIS, A CORPORATION OF ILLINOIS.

DRINKING STRAW.

Application filed July 26, 1920. Serial No. 399,216.

To all whom it may concern:

Be it known that I, HUGO PICK, a citizen of the United States, and a resident of Chicago, in the county of Cook and State of 5 Illinois, have invented certain new and useful Improvements in Drinking Straws, of which the following is a full, clear, and exact description.

The invention relates to drinking straws.

10 The object of the invention is to provide a drinking straw in which the mouth portion is clearly distinguishable or marked, so that persons serving or handling the straws before they reach the user will refrain from touching the mouth portions.

15 With this object in view, the invention consists in the improved drinking straw hereinafter set forth and more particularly defined by claim at the conclusion hereof.

20 In the drawing: Figure 1 is a web from which strips for forming the straws are cut.

Fig. 2 is a perspective of the finished straw.

25 The improved straw is formed of suitable material, such as paper, and is characterized from the straws now in general use by having a portion adjacent one end distinctly marked, as at 3, to differentiate that portion which is to be placed in the mouth of the user from the remainder 4 of the straw. As 30 a result, persons handling the straws in serving them can readily distinguish the mouth portion from the remainder of each straw and refrain from handling the mouth portions so that they will be kept in a sanitary 35 condition.

In making these straws, a web of paper 5 is printed with distinguishing lines or stripes which are colored, as at 6. This web is divided on line 7 to form two strips each with the marking at one margin to form the 40 mouth-ports 3. The ends of these strips are successively severed crosswise, as at 9, to form pieces each adapted to form a straw. Each piece is then folded into tubular form with lapped margins which are then suitably secured together by an adhesive. Then the entire straws are coated with paraffine or the like to render them waterproof. The coating covers the ink in the printing of the marking 3 on the straws, so that there will 50 be no danger of infection therefrom.

45 The invention is not to be understood as restricted to the details set forth, since these may be modified within the scope of the appended claim, without departing from the 55 spirit and scope of the invention.

Having thus described the invention, what I claim as new and desire to secure by Letters Patent, is:

A drinking straw formed of suitably 60 coated paper, having one end portion thereof distinctively marked to differentiate it from the remainder of the straw so that persons handling it will be warned from touching the mouth-portion thereof, said straw being 65 of substantially uniform contour throughout its length.

HUGO PICK.
